CLAIM

The ornamental design for football-shaped binoculars, as shown and described.

DESCRIPTION

FIG. 1 is a bottom view of football-shaped binoculars in closed position, showing our new design;

FIG. 2 is a side view thereof;

FIG. 3 is a top view thereof;

FIG. 4 is an end view thereof, it being understood that the opposite end is a mirror image thereof; and,

FIG. 5 is a perspective view of football-shaped binoculars in open condition.

The broken line showing of environment is for illustrative purposes only and forms no part of the claimed design.
